UNITED STATES PATENT OFFICE.

HENRY M. COLLESTER, OF WORCESTER, MASSACHUSETTS.

DESIGN FOR CANE FABRIC.

SPECIFICATION forming part of Design No. 26,475, dated December 29, 1896.

Application filed November 27, 1896. Serial No. 613,697. Term of patent 7 years.

To all whom it may concern:

Be it known that I, HENRY M. COLLESTER, of Gardner, in the county of Worcester and State of Massachusetts, have invented and 5 produced a new and original Design for Cane Fabric, of which the following is a specification.

Reference is to be had to the accompanying drawing, forming a part of this specification, 10 which shows a piece of cane fabric with my design applied.

The leading feature of my design is the arrangement of the intersecting stripes *a* and *b*, of contrasting color from the body of the 15 fabric, producing polygonal figures whose angles are arranged between the adjacent arms of cross-shaped figures *c*, produced by the intersection of the stripes.

f represents a piece of cane fabric bearing

my design, which consists of the intersecting 20 stripes *a* and *b*, of contrasting color from the body of the fabric *f*. The arrangement of these stripes is such as to produce squares *f'*, whose angles are arranged within the adjacent arms of cross-shaped figures *c*, formed 25 by the intersection of the stripes *a* and *b*.

I claim—

The design for cane fabric, as herein shown and described.

In testimony whereof I have signed my 30 name to this specification, in the presence of two subscribing witnesses, this 18th day of November, A. D. 1896.

HENRY M. COLLESTER.

Witnesses:

EDWARD G. WATKINS,
THATCHER B. DUNN.
